UNITED STATES PATENT OFFICE.

ELIHU THOMSON, OF LYNN, MASSACHUSETTS.

ELECTRIC-LIGHT POLE.

SPECIFICATION forming part of Letters Patent No. 393,040, dated November 20, 1888.

Application filed June 9, 1888. Serial No. 276,648. (No model.)

To all whom it may concern:

Be it known that I, ELIHU THOMSON, a citizen of the United States, and a resident of Lynn, in the county of Essex and State of Massachusetts, have invented a certain new and useful Electric-Light Pole, of which the following is a specification.

My invention relates to the construction of posts or poles designed for supporting electric lines or conductors carrying currents of considerable tension.

The object of the invention is to so construct the pole that a person mounting the post may be free from the danger of receiving a shock by forming a ground for the electric current through his body.

To this end my invention consists, essentially, in constructing the post or pole with a section interposed between its pedestal and its top or line-supporting portion and insulated from both, such section being of sufficient length to prevent a person ascending the pole from touching the pedestal or base portion and the portion which supports the line wire or conductor at the same time.

My invention consists, further, in certain details of construction, to be more particularly hereinafter described, and then specified in the claims.

My invention consists, further, in the special constructions and combinations, which will be described in connection with the accompanying drawings, and then specified in the claims.

Referring to the drawings, Figure 1 is a side elevation of a post constructed in accordance with my invention. Fig. 2 is a vertical section through a form of joint which may be employed. Fig. 3 is a vertical section through a modified form of joint. Fig. 4 is a vertical section through the intermediate portion of a post or pole of modified construction, but also embodying my invention.

In Fig. 1 the post is shown carrying an electric light supplied by current from a line-wire, L.

A indicates the base or pedestal portion of the post, which may be conveniently made of cast-iron, and which is in connection with the ground.

C indicates the top or line-supporting portion, which part may be of greater or less

length, as desired. Interposed between these two portions is the section B, insulated both from the pedestal A and from the part which forms the upper portion of the post and supports the electric line. The intermediate section, B, should be of such length that a person ascending the post cannot, while in connection with the pedestal A, reach to the upper section, C. One intermediate section may be employed, as indicated at B, though it will be obvious that the intermediate section, B, might be divided into two or more sub-sections.

It will be found sufficient in practice to make the section B about seven feet in length.

The pole may be provided with steps, as usual, to facilitate ascent and descent in connection with the examination or rearrangement of the line or the apparatus supported by the post.

A form of joint which may be used between the sections B and C is shown in Fig. 2. One section, C, is cup-shaped at its lower end, and is made somewhat larger in diameter than the upper end of the section B, which it receives. The space between the two sections is filled with an insulating or cementing compound, which can be cast in position, and may be formed, for instance, of a mixture of sulphur and sand, although obviously other materials may be employed.

To assist in the insulation, the lower end of the section C is made to form at F a depending flange or water-shed to prevent the formation of a connection between the two sections by moisture in stormy or wet weather. This flange or water-shed may be conveniently secured by applying the insulating compound in amounts sufficient to only partially fill the space between the two sections at the joint.

In the modified form of joint indicated in Fig. 3 the insulating compound is cast so as to entirely inclose the upper end of the section B, thus preventing a possible short-circuiting or grounding by particles of metal or moisture which might gain access to the interior of the post when the latter is formed of pipe or is made of any other material in whole sections.

I do not limit myself to the special forms of joint shown, nor to the special means of insulation, since my invention consists, broadly, in the use of one or more intermediate sections be-

tween the pedestal and line-supporting portions, such intermediate sections insulating the pedestal and top portions from one another.

It is obvious that the forms of joint shown in 5 Figs. 2 and 3 might be used between the pedestal A and the next section, B.

In Fig. 4 the intermediate section, B, is shown as constructed of wood, which may or may not be covered with a sheath of iron. It is preferable to apply in this case also a water-shed at one or both joints. In the instance shown in Fig. 4 it is obvious that it is not necessary to apply additional insulating material at the joint between the sections.

25 Any pleasing design may be given to the section of post.

An additional element of safety is secured by making the extreme upper section entirely of wood.

20 Tests may be made from time to time of the insulation of the joints, especially in wet weather, to afford a further safeguard.

The section C may support the line in any desired manner, and may, if desired, be provided with an attached tube or support, to 25 which the line is connected.

What I claim as my invention is—

1. A supporting post or pole for electric lines, having between its pedestal or earth portion and its upper or wire-supporting portion one or more intermediate sections insulated from base and top, and of sufficient length to prevent a person from touching both pedestal and top sections simultaneously.

35 2. A sectional post or pole having at the

joints of the insulated sections a depending flange or water-shed, as and for the purpose described.

3. An electric-line post or pole having an interposed section between its top and pedestal, 40 insulating the one from the other, and of sufficient length to prevent a person from touching both at the same time.

4. An electric-line post or pole made in three or more cast-iron sections, those sections above 45 the pedestal having each a cup-shaped lower end adapted to receive the top of the section beneath, together with a suitable interposed cementing or insulating material.

5. An electric-line post or pole having its 50 pedestal insulated from its line-supporting portion by a space greater than the reach of the person climbing the pole.

6. In an electric-line post or pole, the combination, with the base or pedestal, of two or 55 more superposed sections, each having a socket at its lower end, and insulating or cementing material in said socket, as and for the purpose described.

7. A sectional electric-line post or pole having the end of one section which enters another entirely inclosed in insulating material, as and for the purpose described.

Signed at Lynn, in the county of Essex and State of Massachusetts, this 21st day of May, 65 A. D. 1888.

ELIHU THOMSON.
